[57] CLAIM

The ornamental design for an electric cord reel, substantially as shown and described.

DESCRIPTION

FIG. 1 is a side elevational view of an electric cord reel showing my new design;

FIG. 2 is an end view thereof;

FIG. 3 is an elevational view thereof from the side opposite that shown in FIG. 1;

FIG. 4 is a sectional view taken along line 4—4 of FIG. 2; and

FIG. 5 is a sectional view taken along line 5—5 of FIG. 3.

Fig. 1

Fig. 2
